(57) **CLAIM**

The ornamental design for a radiant heat floor panel, as shown and described.

DESCRIPTION

FIG. 1 is a top left perspective view of a radiant heat floor panel incorporating the new design.

FIG. 2 is a top right perspective view of the panel of FIG. 1. FIG. 3 is a top perspective view of a radiant heat floor panel shown in FIGS. 1-2, attached to like panels and used in a floor. The floor is shown for environmental purposes only and forms no part of the claimed design.

FIG. 4 is a top left perspective view of a first alternative radiant heat floor panel to that of FIG. 1.

FIG. 5 is a top right perspective view of the panel of FIG. 4. FIG. 6 is a top perspective view of a radiant heat floor panel shown in FIGS. 4-5, attached to like panels and used in a floor. The floor is shown for environmental purposes only and forms no part of the claimed design.

FIG. 7 is a top left perspective view of a second alternative radiant heat floor panel to FIG. 1.

FIG. 8 is a top right perspective view of the panel of FIG. 7; and,

FIG. 9 is a top perspective view of a radiant heat floor panel shown in FIGS. 7-8, attached to like panels and used in a floor. The floor is shown for environmental purposes only and forms no part of the claimed design.
